CABINET CONSTRUCTION

Jack Belden Keck, Sioux City, Iowa, assignor to Curtis Companies Incorporated, Clinton, Iowa, a corporation of Iowa

Application April 14, 1958, Serial No. 728,222

4. Claims. (Cl. 312—263)

This invention relates to cabinets of the type that may be permanently installed in homes, particularly in kitchens, although they are suitable for general use. The primary object of the invention is to provide a cabinet which is sturdy, simple in construction and easy to build on semi-automatic machinery.

Another object is to provide a cabinet having a continuous wall panel forming the back and sides and joined to top and bottom members by means of an improved joint construction.

These and other objects will become apparent from the following description when read in connection with the accompanying drawings, wherein:

Figure 1 is a perspective view of a cabinet construction in accordance with the invention;

Figure 2 is a perspective exploded view of the corner joint construction;

Figure 3 is a sectional view of the corner joint taken through the wall panel parallel to the bottom of the cabinet;

Figure 4 is a sectional view taken along the line 4—4 of Figure 3; and

Figure 5 is a sectional view taken along the line 5—5 of Figure 3.

The cabinet consists of a top plate or frame member 10 having three kerfs extending parallel to and spaced inwardly from the side and rear edges thereof. The bottom of the cabinet comprises a plate 18 having similar kerfs cut in the face thereof. The frame member 10 is usually replaced with a continuous top in wall cabinets. The base cabinet shown in the drawing is adapted to carry a plastic or linoleum covered top (not shown). The members 10 and 18 illustrated in the drawing are made of plywood but can be made from a single thickness. Since the top frame 10 is rectangular, the side kerfs 12 cross the rear kerf 16 at an angle of 90°. In cutting the kerfs it is not necessary to stop the cut at the point where it joins the adjacent kerf. It will be noted that the kerfs extend completely across the frame 10 in both directions. This avoids the time and care required to cut accurately to the adjacent joint. Bottom plate 18 is identically grooved.

The kerfs form a continuous groove which is adapted to receive the side wall 20 of the cabinet. Although the kerfs extend only to three sides in the particular construction shown in the drawing, it will be understood that they may extend partially across the fourth or front side if desired. Usually, however, the front of the cabinet is covered by doors 21 which extend completely across the front.

The back and the two sides of the cabinet are formed from a single panel 20 preferably made from pressed cellulose board or the like. The material is of the type that can be moistened or steamed in order to shape it to a relatively sharp radius without fracture. The thickness of the sheet 20 is slightly less than the width of the kerfs cut in the top and bottom members 10 and 18. It should fit snugly in the groove or channel provided by

2

the kerf. The kerf may be bevelled as indicated at 23 to facilitate assembly of the panel 20 with members 10 and 18.

To obviate the necessity of providing an arcuate kerf 5 to accommodate the curve of the sheet 20 at the corners where the sides join the back, and the necessity for accurate location of said corners with respect to the kerf, the panel forming the side wall is not seated in the kerf at the corners. This is accomplished by providing cut-out portions 26 coextensive with the corners (Figure 2). The depth of the cut-out 26 is approximately equal to the depth of the kerf. Consequently, when the marginal edge of sheet 20 is seated in the kerfs or channel, the bottom of the cut-out portion 26 is flush with the surface of the member in which the kerf is cut, as best shown in Figures 4 and 5.

The advantage of this construction is at once apparent. The sheet 20 may be formed on a first machine to provide a radius of curvature along the line where the back 20 and sides of panel 20 merge. On a second machine the top and bottom members 10, 18 are then pressed from both sides onto the ends of the sheet 20, while the sides are held at 90° to the back. The kerfs are preferably daubed with glue to provide a very tight joint between the top and bottom and the sheet 20. The cut-out portion 26 is sufficiently wide so that it extends for a distance slightly beyond the point where the radius of the corner tangentially meets the kerfs 12 and 14. This construction avoids the necessity of accurately fitting the continuous wall panel forming the back and sides to the plates.

Additional reinforcement to hold the cabinet together is provided by supporting stiles 28 which are located at a plurality of points outside of the continuous side wall formed by the sheet 20. Two of the stiles are located at the open front of the cabinet to provide an anchoring piece for the doors. The other two are located near the rear of the cabinet on the sides. They are nailed and glued to the sheet 20 prior to shaping and assembling 35 with the top and bottom, and are nailed to the top and bottom members after assembly. Doors 21 of any suitable design are hinged to the stiles 28 to close the front of the cabinet. Preferably, the doors are hinged by means of the type which swing from a point spaced 40 outwardly from the face of the cabinet so that cabinets 45 may be installed side by side without interference between adjacent doors when they are being opened.

Although pressed cellulose board has proved to be very satisfactory for the side wall of the cabinet, it will be understood that any material which has sufficient strength and which is capable of being shaped to a relatively sharp radius can be used for purposes of the invention. The curved corners provide a very pleasing appearance and facilitate cleaning the interior of the cabinet. There 55 is no possibility of dirt lodging in the corners, which is the case where the side wall is formed from individual back and side panels.

The interior of the cabinet can be arranged with shelves, racks or other pieces of equipment desired to 60 meet the need for storing any particular kind of articles.

Other modifications of the invention will occur to those familiar with cabinet construction. There is no intention to limit the invention to the specific forms shown other than as necessitated by the scope of the 65 appended claims.

What is claimed is:

1. A cabinet comprising opposed, generally rectangular end members joined by a continuous wall panel forming the back and two sides of the cabinet, said panel 70 having a curved corner between said back and said sides, each of said end members having three kerfs cut in the face thereof and being joined at right angles to

provide a continuous channel for receiving the edge of said panel, said edge being cut out at said curved corners to a depth approximately equal to the depth of the kerf so that said edge is seated in said kerf except at said corners.

2. A cabinet comprising opposed, generally rectangular flat end members joined by a continuous wall panel forming the back and two sides of the cabinet, said panel having a curved corner between said back and said side, each of said end members having three kerfs cut in the face thereof and being joined at right angles to provide a continuous channel for receiving the edge of said panel, said edge being cut out at said curved corners to a depth approximately equal to the depth of the kerf so that said edge is seated in said kerf except at said corners, and a

plurality of supporting stiles extending between said end members outside said panel.

3. The cabinet of claim 2 wherein said panel is made from a single sheet of compressed cellulose board.

4. The cabinet of claim 2 wherein said supporting stiles are secured both to said end members and to said panel to provide a unitary structure.
